Mr. J. H. H.

W. H. Thun

Design for Casting Patented April 22, 1901

Mar. 784

William H. Green, of Meriden, Conn.
Letters Patent No. 784. Dated April 22, 1856.

The schedule referred to in these Letters Patent, and
making part of the same.

To all whom it may concern:

Be it known, that I, William H. Green, of the town of Meriden, in the County of New Haven, and State of Connecticut, have invented or produced a new and original design for a basket, and I do hereby declare that the following is a full and exact description of the same; reference being had to the accompanying drawings, and to the letters of reference marked thereon.

The nature of my design or invention

differs from all other casters, in having the bottles or cruets revolve round a horizontal quidgeon or journal, instead of a perpendicular stem, the rotary motion being diminished by means of slots in the arms or spokes of the revolving wheels, that support the bottles or cruets, as designated in the accompanying drawing, by letter A. in Figure No. 1, or by a piece of tubing, sliding up and down a rod attached to each arm or spoke of said wheel as designated by letter A. in Fig. No. 2, and steadied by a spiral spring, whereby the rings or cups containing the bottles or cruets gradually approach the centre as they rise and fall from the centre as they are lowered, thereby giving additional weight to the lower arms or spokes of the wheels.

Figures No 1 & 2, are geometrically designed wheels, two of which are made fast at the centre to a piece of tubing.

Figure No. 3, is a side view of the ornamental stand or base, letter B, is the nut that is screwed on to the quidgeon or journal.

Figure No. 4, is an end view of the stand or base, through which the bottles or cruets revolve round the quidgeon or journal, marked letter C. Letter D, the pivot on which the bottles turn, to preserve a perpendicular position, &c, the spiral springs.

What I claim as my invention or production, and desire to secure by letters patent, is the general design and configuration of the caster.

Witnesses.
